FURNACE

Percival B. Crocker, Taunton, Mass., assignor to
The Sentry Company, Taunton, Mass., a cor-
poration of Massachusetts

Application July 30, 1931, Serial No. 554,023

5 Claims. (Cl. 219—36)

This invention relates to furnaces and in its more specific aspects to electric tube furnaces, particularly those designed to operate at high temperatures for combustion analysis and similar work. The object of the invention is to provide improvements in the construction of furnaces having various advantages in manufacture and use, as will appear from the following description.

10 My invention will be well understood by reference to the following description of an illustrative embodiment thereof shown by way of example in the accompanying drawings, wherein:—

15 Fig. 1 is a perspective view of the furnace; Fig. 2 is a central longitudinal section on a larger scale with part broken away;

Fig. 3 is a longitudinal section on one side of the center through one of the resistance 20 elements;

Fig. 4 is a transverse section looking toward the front of the furnace; and

Fig. 5 is a section through one of the elements which forms a heating chamber taken on the 25 line 5—5 of Fig. 4.

The furnace which I am about to describe may be briefly characterized as comprising a heating chamber suitably insulated exteriorly in which is disposed a muffle for the work to be heated 30 and heating elements disposed in the chamber adjacent to the muffle.

Referring to Figs. 2 and 3 of the drawings, the heating chamber may comprise front and rear end elements 9 and 11 of fire-brick or 35 similar refractory material which may be provided (see Figs. 4 and 5) with lower flanges 13 and lateral flanges 15 for the support of the bottom slab 17 and side slabs 19 of refractory material, the latter supporting the top slab 21, 40 and these four slabs in cooperation with the end elements 9 and 11 forming the heating chamber. The elements 9 and 11 are provided respectively with the projections 23 and 25 on their exterior faces which are received in openings in the frame-like end plates 27 which may be connected by bolts 29 (Fig. 1) holding the various parts in assembled relation. The end plates 27 may be formed with legs 30 supporting the furnace chamber in a convenient elevated 45 horizontal position. Interposed between the end plates 27 is a light metal casing 31 serving to retain heat insulating material 33 about the heating chamber.

It will be seen by comparison of Figs. 2 and 3 50 that the sides of the end elements 9 and 11 may

be bevelled off toward the side of the projecting portions 23 and 25, giving them a substantially frusto-pyramidal form and permitting the insulating material 33 to extend partly over the ends of the chamber which thus retains the heat 60 better.

As seen from Fig. 4, the end elements 9 and 11 are provided at the location of the projections 23 and 25 with suitable openings, herein a central opening and two lateral openings, providing respectively for the reception of the muffle tube 35 and the heating elements 37, which latter preferably take the form of resistor bars of silicon carbide. Referring to Fig. 3, the openings 39 through the end elements 9 and 11 which receive the resistor bars are preferably chamfered interiorly as shown to reflect heat generated in the ends of the heating elements back to the furnace chamber and also to facilitate placing and centering of the bars, and the bars 75 37 extend in these openings through the greater portion of the thickness of the end wall to adjacent the outer boundary thereof. As seen at the left of the figure, one end of bar 37 is supported by a terminal 41, the end of which 80 enters for a short distance in the opening 39 and the outer end of which abuts against a plate of non-conducting material 43 supported in spaced relation from the front of the furnace by studs 45 and 47. A similar terminal 85 49 slightly entering opening 39 in the rear end member 11 engages the rear end of resistor bar 37 and a spring 51 carried by cross-bar 53 at the rear of the furnace presses against this terminal and compressing the parts against the 90 abutment 43 retains the resistor bar in position. An electric connection at 55 supplies current to one of the resistor bars and the current may pass through the cross-connection 57 at the front of the furnace behind the shield 43 95 to the resistor bar at the other side and goes to the other side of the line through a connection similar to 55 at the rear of the furnace. In the arrangement shown the heating element comes sufficiently far to the outside of the furnace so 100 that the end is somewhat cooled and danger of corroding the terminals is lessened. At the same time the terminals 41 and 49 do not extend sufficiently far into the heating chamber to be corroded. To provide for cooling the terminals, 105 their exteriorly exposed surfaces are preferably provided with heat-radiating fins as shown.

An important feature of my invention is the form of muffle tube 35. This comprises a main cylindrical body 59 which may pass through an 110

opening in front of the end element 9 and through opening in plate 43, as best shown in Fig. 2. It will be understood that the material to be heated may be inserted in the muffle through the open end of the tube which is exposed at the front. The rear end of the tube, however, is preferably reduced in diameter before it passes through the rear wall 11. Herein the tube is provided with the reduced cylindrical portion 61 of considerably less length than the thickness of the rear wall providing a supporting bearing for the tube in that wall and defining with the main body of the tube a shoulder 63 which herein is received in the chamfered portion 65 of the central opening to the said rear wall. The end of the tube is again reduced within the distance represented by the thickness of the rear wall of the furnace, there being herein shown a conical portion 67 merging with the cylindrical portion 69 which extends out at the rear of the furnace, the projecting end providing for the connection of a rubber tube thereto to receive gaseous products from the muffle, as is customary, for instance, in the practice of combustion analysis.

When the muffle tube is constructed in this manner there is a marked reduction in the heat emitted from the furnace. This saving in heat gives better furnace economy as the chamber requires less heat energy, reducing the amount of energy which must be supplied to the furnace and thus reducing the cost of operation. The saving in heat lowers the temperature at the extreme end of the tube, reducing the danger of burning the rubber connection tube, and permits the connection of the latter tube to be made in close proximity to the furnace. This in turn, by minimizing the necessary length of projecting tube, reduces the danger of breakage.

The saving of heat is in conduction, convection and radiation. With respect to loss of heat by conduction, this is, of course, in proportion to the cross section of the conducting material, and as the reduction in diameter of the annular section of the tube reduces the area proportionally to the square of the radius, the restricted tube has much less material in its wall to conduct heat. Less heat is lost by convection currents as the tube is small and air currents are not so free to circulate about inside the tube and carry heat from the heated interior section to the cool exterior portion. Less heat is lost by radiation. Radiant heat travels in straight lines, as does light. The interior surface of the shoulder 63 at the interior of the furnace will stop practically all of the radiant heat and prevent its falling on the unheated outside section.

I am aware that the invention may be embodied in other specific forms without departing from the spirit or essential attributes thereof, and I therefore desire the present embodiment to be considered in all respects as illustrative

and not restrictive; reference being had to the appended claims rather than to the foregoing description to indicate the scope of the invention.

I claim:—

1. A furnace of the class described comprising refractory end elements having exterior projections, refractory means between said end elements cooperating therewith to define a chamber, end plates having openings receiving said projections, means connecting the end plates to hold the parts assembled, said end elements having suitable openings at the location of said projections providing for introduction of work to the chamber and for connection to heating elements therein. 80

2. A furnace of the class described comprising refractory end elements having exterior projections and interior flanges, refractory slabs positioned by said flanges to define in cooperation with said elements a chamber, end plates having openings receiving said projections, means connecting the end plates to hold the parts assembled, said end elements having suitable openings at the location of said projections providing for introduction of work to the chamber and for connection to heating elements therein. 85 90

3. A furnace of the class described comprising refractory end elements of substantially frusto-pyramidal form and having projections at their smaller bases, refractory means between said end elements cooperating therewith to define a chamber, end plates having openings receiving said projections, insulating material surrounding said chamber between the end plates, means connecting the end plates to hold the parts assembled, said end elements having suitable openings at the location of said projections providing for introduction of work to the chamber and for connection to heating elements therein. 100 105 110

4. A furnace of the class described comprising refractory end elements of substantially frusto-pyramidal form having flanges at their larger bases, refractory slabs positioned by said flanges to define in cooperation with said elements a chamber, end plates engaging said elements at their smaller bases, insulating material surrounding said chamber between said end plates, means connecting said end plates to hold the parts assembled, said end elements having suitable openings providing for introduction of work to the chamber and for connection to heating elements therein. 115 120 125

5. An electric furnace having openings in opposed walls thereof, one of said openings being internally chamfered, and a muffle tube having a cylindrical body extending through an opening, said body being reduced to provide a shoulder entering the chamfered portion of the other opening and a reduced extension projecting out through the wall. 130 135

PERCIVAL B. CROCKER.
